UNITED STATES PATENT OFFICE.

GEORGE TUCKER, OF BIRMINGHAM, AND JOSEPH FREDERICK JONES, OF ASTON, NEAR BIRMINGHAM, ENGLAND.

MACHINE FOR MAKING LACING-HOOKS, &c.

SPECIFICATION forming part of Letters Patent No. 746,901, dated December 15, 1903.

Application filed May 26, 1902. Serial No. 109,045. (No model.)

To all whom it may concern:

Be it known that we, GEORGE TUCKER, manufacturer, of Jameson road, Nethells, Birmingham, and JOSEPH FREDERICK JONES, tool-maker, of 169 Church Lane, Aston, near Birmingham, England, both subjects of the King of Great Britain, have invented a certain new and useful Machine for Making Lacing-Hooks and Like Small Articles, of which

10 the following is a specification.

This invention has relation in the first part to the manufacture or production of metallic eyelet-hooks or lacing-hooks and boot-fasteners and is also applicable to the production of other analogous small metallic articles from sheet metal, and in the second part to the machinery and tools to be employed in the production of such lacing-hooks and the like in accordance with the process

20 which constitutes the first part of the said invention.

The principal object of the invention is to reduce the cost of manufacture or production of the said articles, and this it is proposed to accomplish by performing the whole of the different stages or processes or the full sequence of operations necessary for the production of a given article simultaneously by a complete set of tools worked in a single machine and corresponding in number to the number of operations involved, so that once the machine has been fully started a completely-finished article is produced with every stroke of the tool-slide. Thus at each stroke 30 of the machine the several stages of production are performed all at the same time or simultaneously, but upon different successive parts of a strip of metal which is fed into and through the machine lengthwise and progressively or by intermittent steps, and, assuming that an article requires to be operated upon by seven different tools or submitted to seven different processes to complete its manufacture from the strip to the

40 finished form, this number of tools is arranged in the one machine so as to operate simultaneously upon the different successive portions of the said strip, whereby the flat metal fed in at one end of the machine is progressively fashioned or worked up as it passes

through and the completely-finished articles are delivered one at a time at the other end.

We propose to describe the application of our invention to the manufacture of a lacing-hook or hooked eyelet for boots, this article 55 comprising an eyelet with a hook-shaped head having a domed top and connected to the edge of the eyelet by a crinkled web.

A machine adapted for the production of a lacing-hook in accordance with our improved process or method is represented in the accompanying drawings, in which—

Figure 1 is a front elevation, one only of the dies being shown in transverse vertical section. Fig. 2 is another view of the complete machine, partly in elevation and partly in vertical section, to show the arrangement of the series of bottom dies, the method of mounting and working the corresponding series of top tools or punches in the reciprocating tool-slide, and the construction of the feed-motion for passing the strip of metal progressively between the top and bottom tools. Fig. 3 is a view showing the side of the machine at which the feed-motion is arranged. Fig. 4 represents a vertical section of the machine upon the dotted line x, Fig. 2, showing the cross-slide, in which the last die of the bottom series is formed, in its rearward or withdrawn position. Fig. 5 is a similar sectional view to that represented in Fig. 4, but shows the die-slide in its forward or advanced position. Figs. 6 and 7, respectively, represent in longitudinal section and in plan a portion of the strip, showing how

80 the different parts as they pass through the machine are progressively fashioned or worked up by the succession of stages or processes involved in the production of the eyelet, commencing with the initial cupping of 85 the flat metal and ending with the cutting out of the pierced eyelet and head. Fig. 8 is an edge view of the cut-out eyelet and head, which in order to complete the formation into the finished hook has to be bent up 90 transversely across the web which connects the eyelet part with the domed head. The finished article is shown in elevation and plan view in Fig. 9.

The same letters of reference indicate cor-

100

responding parts in the several figures of the drawings.

The bed *a* of this machine is provided with a series of five fixed bottom dies or die-matrices *b c d e f*, set with their vertical centers at exactly equal distances apart and having their respective sinkings *b' c' d' e' f'* shaped to correspond in form and depth with the shapes that have to be imparted in succession to each portion of the fed-in strip *i* in the course of the preliminary cupping and piercing processes involved in the production of a lacing-hook of the desired pattern. Thus the dies *b, c, d*, and *e* are designed to respectively impart to the strip the cuppings indicated at *i' i'' i''' i''''* in Figs. 6 and 7, while the die *f* is for piercing or knocking out the bottom of the cup, as shown at *i''''*, and beyond the piercing-die is arranged an open-bottomed or cutting-out die *g*, which cuts out the shaped eyelet with its integral web and hook-head at *i''*, it being understood that the several die-matrices are spaced out or set at distances apart which will leave sufficient flat metal between the cuppings to provide for the formation of the domed head by the tool provided for the purpose, as hereinafter described. Also located in the bed of the machine and adapted to work to and fro underneath the open-bottomed die *g* is a cross-slide *h*, fitted with a bending-die *h'*, in which the final stage of bending up the cut-out article into the finished form is accomplished. Arranged in conjunction with this set of bottom dies is a corresponding set of top tools or punches *b², c², d², e², f²*, and *g²*, adjustably mounted within the reciprocating tool-slide *j* of the machine, so that the whole of the said tools descend and make their working or operative stroke at the same time. The noses or acting ends *b³, c³, d³, e³, f³*, and *g³* of these punches are formed to correspond with the matrices of the lower dies, with which they are respectively adapted to coöperate. Thus the punches *b², c², d², e²* are cupping-tools, and the punch *f²* is a piercing-tool adapted to knock out the bottom of the cup at the fifth stage of the process, while the punch *g²* is a combination shaping and cutting-out tool and is adapted to both shape the portion of the metal *i''* immediately in front of the eyelet into the domed head of the hook and also to cut out this combined head and eyelet from the strip and force it through the open-bottomed die *g*, this being the last stage of the process so far as these six tools are concerned, as the final stage—viz., the bending up of the hook so that its concavity faces the open end of the eyelet—is performed by a supplementary and separately-operated punch or tool *k*, acting in conjunction with the bending-die *h'* of the cross-slide *h*.

The whole of the matrices of the lower dies *b, c, d*, and *e* have open bottoms, coinciding with vertical holes or wells *b⁴ c⁴ d⁴ e⁴*, made in the bed of the machine and containing spring-operated ejector-stalks *b⁵ c⁵ d⁵ e⁵*, which are

forced downward, and their springs are compressed or made active when the reciprocating punches of the tool-slide descend in making the working stroke; but when the said punches return or ascend the ejector-springs react upon their stalks, and the upper ends being projected simultaneously through the open bottoms of the die-matrices strike against the bottoms of the cupped parts of the strip lying therein and bodily lift the portion of the said strip which is at the time being subjected to the action of the tools to such an extent that the said cupped parts are cleared of the dies and the strip is free to be fed forward a further step—viz., to an extent equal to the distance between the vertical center of any one die and the vertical center of the next die of the series—it being understood that the feed-motion (which is hereinafter described) is so adjusted that after each stroke of the tool-slide it will deliver or pass into the machine a further length of the continuous strip corresponding to the quantity of metal required for the production of a single complete article. To arrest the strip in its upward motion after it has been raised clear of the die-matrices, a guard or stop plate *n* is fixed at the proper distance above the die-bed, this plate being provided with a series of holes within which the reciprocating punches work.

The combined shaping and cutting-out tool *g²* is fitted with a spring-ejector *g⁴*, the stalk *g⁵* of which is adapted to project through a hole *g⁶* in the acting end of the tool as the latter ascends after making its cutting stroke and deliver the domed and eyeleted blank into the bending-die *h'* of the cross-slide, which is then made to advance so as to present the said blank to the action of the tool *k*, which is carried in a separate vertical slide *k'*, reciprocating in guides *k²* at the front of the machine.

The sliding die *h'* has a clearance *h²* in the middle and ledges *h³ h⁴* on the opposite sides of the said clearance for supporting the fashioned blank while it is being advanced from underneath the open-bottomed die *g*, as shown in Fig. 4, to a point below the bending-tool, as shown in Fig. 5, and then when the bending-tool descends it strikes the middle part of the blank, which is forced into the said middle clearance and bent up staplewise, with the hollow of the domed head presented to and standing at a short distance from the mouth of the eyelet. The cross-slide is then retired back to its original position, ready to receive the next cut-out article.

At the bottom of the lower bending-tool there may be formed a rise or projection *h⁵*, which forms a strengthening or stiffening corrugation or cross-crinkle *o²* along the web *o³*, which connects the domed head *o'* to the edge of the eyelet *o*.

An arrangement of tools such as hereinbefore described may be operated by any suitable mechanism; but in the particular form of machine shown in the drawings the whole

of the working parts derive their motion from a main driving-shaft m , working in bearings m' in the frame m^2 and provided with an eccentric m^3 , encircled by a strap m^4 , which is connected at m^5 to the main tool-slide j by a pin m^6 . To the side of this eccentric are a pair of cams $p\ q$, of which the former is adapted to give the forward traverse to the cross-slide h , containing the beading-die h' , while the latter operates the supplementary slide k' , carrying the reciprocating bending-punch k . Thus the cam p , which has a long rest at p' for retaining the cross-slide stationary at the forward end of its stroke for an appreciable period during which bending up of the fashioned blank is performed, acts upon the one arm p^2 of a rocking lever p^3 , fulcrumed to the frame at p^4 and having its lower termination bearing against the back end h^6 of the cross-slide, which is kept close up to the said lever by a spring p^5 , arranged between the slide and a fixed part of the machine and whose function also is to draw back or give the rearward stroke to the slide when the rest part p' of the cam has been taken by the rotation of the main shaft beyond or out of contact with the arm p^2 of the lever. The second cam q has a peripheral projection q' , which is timed to act upon the slide k' after the cross-slide has been advanced and during the period that the rest of the cam p is moving past the arm p^2 of the lever p^3 , and then after the said slide has been thus constrained to make its working stroke for bending up the fashioned blank the return movement is effected by the contraction of a spring q^2 , disposed between the slide and a hook q^3 or other connection fixed to the frame.

The feed-motion for advancing the strip into the machine intermittently and for moving on each of the parts that are being fashioned by the tools to the extent of a further step or stage when the tool-slide ascends after the tools carried by it have completed their simultaneous working stroke is actuated by a third cam r , formed at the end of the main shaft and acting upon a swinging lever r' , fulcrumed at r^2 to the frame. When this lever is rocked in the one direction, the strip is advanced or fed in to the predetermined extent through the medium of a gripper device r^3 , mounted upon a horizontally-reciprocating slide or bed plate r^4 and carrying a pivoted jaw r^5 , which is kept closed to grip the metal by the spring r^6 during the feed movement; but when the lever rocks in the reverse direction the gripper-slide is drawn back by the contraction of the previously-distended springs r^7 and the jaw is momentarily opened, so as to relieve the grip upon the strip by the action of a projection or nose-cam r^8 , disposed adjacent to the cam r and acting upon a slide r^9 , whose foot end r^{10} when depressed impinges against the tail end r^{11} of the gripper-jaw and causes the latter to open. The slide r^9 is taken back to its normal position by the action of the spring r^6 , which also

closes the jaw as soon as the slide r^4 has been drawn back to the limit of its motion by its springs r^7 , and as soon as the said jaw is thus closed onto the strip the mechanism is ready to make the next forward or feed movement. By this arrangement a length of strip equaling the distance between the dies is fed into the machine at each complete revolution of the main shaft, and each such feed brings a fresh or unoperated-upon part of the strip over the first cupping-die of the series and at the same time simultaneously advances each of the several parts which were operated upon by the previous stroke of the machine to a like extent, so as to bring it under the influence of the pair of tools immediately in advance of the pair which performed the previous operation upon it, and thereby each portion of the strip as it passes through the machine is presented or submitted in its proper turn to the action of each set of tools, the whole of which (with the exception of the bending-tools which come into operation while the other tools are ascending) act simultaneously, but upon different parts of the strip, which forms, as it were, a carrier or conveyer for intermittently transferring the shaped portions of the metal onward from die to die after each working stroke of the tool-slide.

From the foregoing description it will be seen that the whole of the parts of the machine are so arranged and timed in their actions that a fashioned hook is finished, bent, and delivered with every complete revolution of the main cam-shaft, and it will be readily understood that by this continuous process or method of producing boot-hooks and the improved machinery used in connection therewith very considerable saving of time and labor is effected, with a corresponding reduction in the cost of manufacture, inasmuch as the blanks do not require to be removed from one machine and transferred to another after each stage or successive operation has been performed; but the strip is carried or fed along for advancing each part to the next successive tool during the upstroke of the tool-slide and then brought to rest prior to the said tools making the descending or working stroke.

The application of our invention to the manufacture of analogous small articles capable of being produced by a succession of stamping and cutting out processes from sheet metal differs in no essential respect from its application to the manufacture of lacing-hooks, as herein described. For instance, in making eyelets and simple articles which require no bending up of a cut-out and fashioned blank to complete the formation the bending-tools and the cross-slide and the mechanism for actuating these parts would be omitted, while in machines for wholly or partially producing such articles as thimbles, ferrules, percussion-cap shells, and small cartridge-cases by the continuous process cupping and clipping or cutting-out tools

only would be required, the tools for piercing the bottom being omitted. In all cases the form, arrangement, and number of the tools would be varied according to the form of the article to be produced and the number and nature of the processes involved in its production.

Having fully described our invention, what we desire to claim and secure by Letters Patent is—

1. In a machine of the character specified, a shaft, a series of tools operated by said shaft, a gripper device consisting of a sliding bed-plate and a gripping-jaw, means for operating said gripper device, a sliding die adapted to coöperate with the last tool of said series, and means for operating said sliding die directly from said shaft.
2. In a machine of the character specified, a shaft, a series, of tools operated by said shaft, a gripper device consisting of a slid-

ing bed-plate and a gripping-jaw mounted thereon, means for intermittently moving said gripper device forward, means for retracting said gripper device, means for releasing said gripping-jaw from its clamping engagement with said sliding bed-plate, while said gripper device is being retracted, a sliding die adapted to coöperate with the last tool of said series, means operated directly from said shaft for moving said sliding die forward, and means for retracting said sliding die.

In testimony whereof we have hereunto set our hands in presence of two subscribing witnesses.

GEORGE TUCKER.
JOSEPH FREDERICK JONES.
